FURNACE FOR BURNING SOLID FUELS SUCH
AS BITUMINOUS COAL AND DERIVATIVES
THEREOF

James A. Worsham, Maplewood, Mo.

Application August 6, 1948, Serial No. 42,844

2 Claims. (Cl. 110—24)

1

This invention relates to improvements in a furnace for burning solid fuels such as bituminous coal, lignite, and derivatives thereof, in sizes from screenings to lumps approximating four to five inches in diameter, the invention primarily being for domestic burning devices although it may go to commercial installations and the like.

The invention also is a furthering of that shown and described in my U. S. application for Letters Patent, filed April 22, 1946, Serial No. 663,973, which issued October 10, 1950, and bears Number 2,524,868.

One of the objects of the invention is to provide a burning device, stove or furnace of an improved construction whereby to first coke a given quantity of coal in one location of the fire pot and to burn the coked coal in another location of the device.

Another object of the invention is to provide the fire pot of the burning device with a pair of cooperating swingable grates, each with a specifically positioned swingable axis so that the steps of treating the fuel in the fire pot will be carried out in the order of coking the fuel, burning the coked fuel and subsequently discharging the burned fuel residue from the fire pot.

A further object is to provide the fire pot of the furnace with a set of two cooperating fuel supporting grates which are swingably mounted on like ends, remote from the fuel firing opening or chute of the furnace.

A still further object is to provide a furnace fire pot with an improved two section grate, one of which is operable to serve as a coking section for coal when fed thereon, and the other section serving as a burning section for the coked coal and subsequently as a shaking and discharging section for the burned coal residue thereon.

It is also an object of the invention to provide the burning section of the grate, of a construction adjacent its swinging axis for engaging or scraping cooperation with any solidifying substance which may form by fuel burning action, on the fire pot refractory wall there adjacent.

Another still further object is to provide the fire pot with an improved swingably mounted baffle wall for diverting the extracting volatiles from the fuel being coked, downwardly into the burning section of the fire pot.

With the foregoing and other objects in view which will appear as the description proceeds, my invention resides in the combination and arrangement of parts and in the details of construction hereinafter described and claimed, it being understood that changes may be made within the scope of what is claimed without departing from the spirit and intents of the invention.

2

An embodiment of the invention is illustrated in the accompanying drawings, wherein:

Figure 1 is a vertical sectional elevation taken through this improved furnace.

5 Figure 2 is a horizontal sectional elevation taken approximately on the line 2—2 of Fig. 1.

Figure 3 is a fragmentary vertical transverse sectional elevation taken approximately on the line 3—3 of Fig. 1.

10 Figure 4 is a fragmentary horizontal sectional elevation taken approximately on the line 4—4 of Fig. 3.

Figure 5 is an enlarged fragmentary vertical sectional elevation taken approximately on the line 5—5 of Fig. 3.

15 Figure 6 is a front elevation of the fuel feed door and damper therefor, taken in the direction of the arrow 6 in Fig. 1.

By reference to the drawings, the numeral 10 designates a hot air type of furnace having the conventional air drum 11 surrounding the burning unit 12 which comprises an ashpit 13 having the fire pot 14 thereabove which leads to the heating drum 15. An outlet 16 from the heating drum 15 leads to a downward extending flue 17 which is in communication at its lower end with the stack 18.

Dividing the ashpit 13 from the fire pot 14 is a normally horizontally disposed two section grate 19, one of said sections being a coking section 20 which is wider than the section 21 which is the combined burning and dumping section. Disposed above the grate section 20 in the refractory wall 22 of the fire pot 14 is a discharge opening 23 which is in communication with the lower end of a fuel chute 24, said chute having its outer extending end extending through the air drum 11 and having a fuel door 25 hinged at 26 thereto.

40 The side of the grate coking section 20 which is remote from the refractory wall 22 is provided with a horizontally extending shaft 27 fixedly secured thereto, said shaft being supported in a pair of bearings 28 and on the end of said shaft which extends through the air drum 11, a lever 29 is secured thereto, outside of the air drum.

The grate section 21 adjacent the refractory wall 30 which is opposite the wall 22 has a horizontally extending shaft 31 forming a part thereof and said shaft paralleling the shaft 27 of the grate section 20 and being supported in a pair of bearings 32, said shaft at one end extending through the air drum 11 and having an operating handle 33 secured thereto, outwardly of the drum 11, said handle being of an inverted L-shape and being of a length whereby the leg 34 will normally engage the floor A when the grate section 21 is horizontally disposed.

The grate section 20 is in the form of a pan having a solid bottom 35 and actually is disposed in the coking section 36 of the fire pot 14, said coking section having a top refractory wall 37 which extends inwardly from the refractory wall 22 to the passageway 38 which extends upwardly from the fire pot.

Swingable by a rod 39 is a baffle wall 40 of a series of refractory panels 41 suspended at their upper ends from a horizontal channel member 42, said member having a pair of upstanding ears 43 which are alined with respective ears 44, secured to and extending from the wall portion 45 of the heat drum 15. A bolt 44a is engaged through an adjacent pair of ears 43 and 44 and one end of the rod 39 is engaged through the other adjacent pair of ears and is secured to the ear 43 of said pair by a pin 43a, the other end of said rod extending outwardly through the air drum 11 and having an operating handle 70.

One side 46 of the channel member 42 is dependingly inclined toward its other side to form a key-way 47 for securing the upper ends of respective panels 41 of the baffle wall 40 which are conformingly shaped to the channel in said member 42, and for mounting the panels 40 in the member 42, a centrally disposed elongated opening 48 is formed in said member.

In mounting the panels 40 in the channel 42 in the event of repair, access thereto can be had through the fire door 49, and the intermediately disposed panel 41 is pushed upwardly through the elongated opening 48 in the channel member 42 and removed therefrom. One of the outer disposed panels is then slid in the channel member 42 to the opening 48 thereof and is similarly lifted through the opening and ultimately the other outer disposed panel is removed in the same manner.

Remounting of panels in the channel member is carried on in reverse order from the removal of the old panels in which the first two panels are engaged in the channel member through the opening 48 and outwardly slid in said member, and finally the centrally disposed panel is inserted through the opening.

Upon readying the furnace for firing a quantity of coal and the required kindling is mounted on the grate section 21 through the fire door 49, air draft therefor being supplied to the ashpit 13 by regulation of the damper 53 on the ashpit door 51. Previous to kindling the fire however, on the grate section 21, a supply of coal is fed through the chute 24 for deposit on the coking section 20 of the grate.

After starting the fire in the furnace and in due time, the damper 52 on the fuel door 25 is regulated to permit air to enter the coking section 36 of the fire pot as the heat from the burning fuel on the grate section 21 becomes effective on the coal which was deposited on the coking grate section 20, thereby expanding and coking the coal in the coking section 36 of the fire pot. The damper 50 on the ashpit door 51 may then be closed so that the only air draft through the burning unit 12 will be through the regulated damper 52 of the fuel door 25.

As the coking of the coal progresses in the section 36 of the fire pot 14, the heavy vapors and gases there arising, will be forced downwardly by the baffle wall 40 and directed thereunder and into the passageway 38 above the grate burning section 21, into combusting contact with the fire thereon and will be ignited and consumed before entering the heat chamber 15.

The coal supply on the coking section 20 of the grate, due to the heat from the fire of the burning fuel on the burning section 21, will ignite the coking coal in the coking section 36 of the fire pot, and particularly by reason of that portion of the coked fuel which overlapped and mingled with the fuel on the grate section 21 when the coal supply was delivered onto the grate section 20, the heat from the combusting fuels of both grate sections 20 and 21 upon passing upwardly through the passageway 38, being directed to one side of the heat chamber 15 by the deflecting refractory wall 53 which is disposed on top of the wall 30, thereby preventing short-cut travel of the heated products of combustion from the heat chamber 15 to the furnace outlet 16.

If the kindled fuel on the grate burning section 21 has been consumed by the time the coal on the coking section 20 has ignited, the ash content or residue on the section 21 can be discharged into the ash can 54 in the ashpit 13 by lifting the handle 33 on the shaft 31 of said section 21, in the manner as shown in dotted lines in Fig. 1.

After freeing the burned residue from the grate section 21, the leg 34 of the lever 33 of said section upon being released, will automatically fall into its neutral position by reason of said leg being of relatively heavy construction and the grate section 21 will be moved to its horizontal position thereby, said grate section then being ready for reception of the coked coal or fuel on the grate section 20.

In discharging the ignited coked fuel from the grate section 20, the handle 29 is manipulated upwardly, thereby inclining the section 20 into a position of discharge so that the burning coked fuel will be dumped on the burning grate section 21 and the handle 29 and grate section 20 is then returned to its neutral position ready for another supply of coal which is fed onto the section 20 through the coal chute 24.

Timely alternate fuel charging from the coking section 20 and subsequent discharging operations of the burning section 21 of the grate 19 commensurate with weather conditions, is carried out in this improved furnace through the burning seasons of the year, and at times upon inspection through the fire door 49 of the burning fuel on the grate section 21, it may be found desirable to shake said section to discharge the ashes therefrom and retain embers that are still burning. This is done by swinging the drop-handle 55 outwardly from the leg 34 of the handle 33 to which it is swingingly attached, thereby raising the handle 33 up and down in short strokes so that the bottom of the leg 34 on the handle will be jarred against the floor A, thereby shaking the finer burned particles from the burning grate section 21 and still retaining the burning embers thereon. After the shaking operation on the grate section 21, the coked fuel on the grate section 20 is discharged onto the burning grate section 21 and of course subsequent coal charging of the grate section 20 is then effected.

The fuel door 25 and the ash pit door 51 and their respective dampers 52 and 50, are very similar in construction, the fuel door 25 being hinged at 26 to the outer extending end of the chute 24 and having a closing plate 56 against which the turnable damper 52 is mounted, said damper having air openings 57 to aline with like air openings 58 in the plate 56 for adjustable alignment with the openings of the damper 52.

An auxiliary door 59 for closing cooperation with the plate 56 is swingably mounted at 60 to the closing plate 56 of the door 25, and attached at 61 to the door 59 is one end of a pull-chain 62, the other end of which may be hand operated or attached to a thermostat control element or the like, not shown.

The ash pit door 51 has an auxiliary door 63 hinged thereto at 64 to which one end of a control chain 65 is attached. The auxiliary doors 59 and 63 of respective fuel and ash pit doors 25 and 51 are operated to regulate the amount of draft air passing through respective dampers of the fuel door and the ash pit door therefor, the respective dampers 52 and 50 of said doors when adjusted for desired air draft regulation, may be left in their adjusted positions so that further regulation therefor is provided by the auxiliary doors only of said fuel and ash pit doors.

It is to be noted that the shaft 31 of the burning grate section 21 is disposed a short distance inwardly on the grate section from the refractory wall 30, thereby providing short portions 66 at that end of each grate bar 67 which at their ends approximately abut the wall 30 although they are each rounded on their under sides, as indicated at 68, for swinging clearance when the section 21 is downwardly swung for residue dumping while the ends of said portion 66 are left sharp or right angular in shape, as indicated at 69 in Fig. 5.

The sharp portions 69 of the short portions 66 of the grate section 21 are for the purpose of breaking off and thus preventing a line of solidifying substance formed by burning products of combustion on the refractory wall 30.

As may be desired, due to the different kinds of fuel used, the baffle wall 40 may be of different length or depth for conditioning the coking section 36 of the fire pot for more suitably carrying on the coking and expanding of the fuel in acquiring all of the volatiles or heavy vapors and oils therefrom, which are more or less present in different fuels, as it is requisite that all of the heavy vapors from the expanding fuel be discharged therefrom and consumed by burning action, before the coked fuel is discharged onto the grate burning section 21, so that there will be no smoke discharged from the furnace through the stack 18.

The fire door 49 may be provided with the form of damper construction referred to in connection with the fuel door 25 and the ash pit door 51, so that regulated air draft into the fire pot passageway 38 may be had.

The baffle wall 40 being swingable, will permit the discharge of coked fuel thereunder from the coking grate section 20 to the burning grate section 21, said baffle wall being rearwardly swung by gravity to its perpendicular position. If necessary however, the baffle wall may be operated by its lever 70.

What I claim is:

1. A furnace comprising a fire pot, a horizontal grate consisting of a front coking section and a rear burning section for said fire pot, means for rotatably supporting said burning section adjacent its rearmost side for dumping burned residue therefrom over its front side, means forming an ash pit for the furnace, air inlet control damper means for the ash pit of the furnace to supply air for starting a fire, means for rotatably supporting said coking section adjacent its rearmost side and so arranged that upon rotation the coked fuel material will be placed by 75

gravity on said burning section, a baffle swingably mounted in said fire pot and disposed in a plane in substantial alignment with the rotational axis of the burning section, said baffle directing the coking gases over the burning section for combustion, a fuel tube for introducing fuel into said coking section, said fuel tube having an air supply opening, air control means in said fuel tube for damping the air supplied to the coking section and through the fuel to continue combustion in said furnace; and a door for said fire pot disposed above said burning section for access thereto in starting a fire and for inspection of the swingable baffle.

5 2. A furnace comprising a fire pot, a horizontal grate consisting of a coking section and a burning section for said fire pot, means for rotatably supporting said burning section for dumping burned residue therefrom, a handle for 10 rotating said burning section and returning it to the horizontal position, means forming an ash pit having an air supply opening for use in starting a fire in the furnace, an air supply damping means for the ash pit air supply opening to the 15 furnace, means for rotatably supporting said coking section and so arranged that upon rotation the material will be placed on said burning section, a baffle including a plurality of baffle blocks swingably hung in said fire pot above and 20 disposed in a plane in substantial alignment with the rotational axis of the burning section to direct combustible gases into the latter section, a fuel and air inlet tube for introducing fuel onto said coking section and supplying air thereto, 25 air inlet control means in said fuel tube for damping the air supply during starting and for thereafter supplying the primary combustion air to said furnace; and a service door for said fire pot disposed above said burning section, said 30 blocks being installed and removed from said baffle through said door.

JAMES A. WORSHAM.
